SYSTEM FOR STORAGE AND UTILIZATION
OF FUEL GASESCharles MacSporran, Detroit, Mich., assignor to
Phillips Petroleum Company, a corporation of
Delaware

Application April 21, 1941, Serial No. 389,642

7 Claims. (Cl. 62—1)

This invention relates to a system for storing and utilizing volatile liquids and liquefied gases. Liquefied petroleum gases, especially propane, butane, and mixtures of the two, are extensively marketed for use as fuel in communities where natural gas is not available. In making use of this liquefied gas for operating gas-consuming appliances, it is customary to provide the customer with one or more containers for storage of the liquefied gas and means for establishing connection between the containers and a service line through a suitable arrangement of valves and pressure regulators. Those installations, in which a single container is used, hereafter referred to as a "one-drum" system, usually comprise a large container which is refilled from a tank truck by a service man. Two types of systems employing a plurality of containers are widely used; one, the "two-drum" system and the other, the "self-service" system. In the two-drum system the customer is provided with two cylinders, each containing a quantity of liquefied gas sufficient to last the customer for a considerable period of time. One of the cylinders is used as an active source of gas supply while the other cylinder is held in reserve until the first cylinder is exhausted. When one cylinder is emptied, a change-over of withdrawal connections is made and the reserve cylinder placed into service. During the time this second cylinder is in service, supplying gas, the empty cylinder is replaced with a filled cylinder. Due to the size and weight of the cylinders, and the necessity of skill and care in installing them properly, they are serviced and handled by service men. The self-service system which has been developed, operates on the same principles as the two-drum system. The customer is provided with two or more containers which he replaces with filled containers when they become emptied. The self-service system, however, employs small containers which the customer can easily handle and the valves, connections, etc., are so improved and simplified that even the inexperienced may make the connections and adjustments necessary to place the containers in operative position. The customer buys the liquefied gas in a suitable container from his dealer, transports it to the place of service, uses the gas formed by vaporization of the liquefied gas, and returns the empty containers to the dealer.

The disadvantages of the one-drum systems and the two-drum systems are that they require the attention of a service man to deliver the liquefied gas to the place of use and put it in

position for use by the customer. They also require the attention of a skilled service man occasionally for repairs and adjustments, especially of the valves. The self-service system requires very little attention other than that which the customer must give it to insure an unfailing gas supply. The valves which are most subject to wear and deterioration are attached to the self-service container and may be examined and tested by the dealer each time the container is returned to him for refilling. It is evident that the self-service system is economically advantageous and may be successfully used in communities in which the population or number of customers is not sufficient to warrant the investment and operating expense required by the other two systems. However, the self-service system has one disadvantage in common with the two-drum system, i. e., the connection between the container and the customer's service pipe involves the use of a flexible coupling which is subject to deterioration and which may become hazardous if not given sufficient and proper attention.

25 An object of this invention is to provide an improved system for storage and utilization of volatile liquids and liquefied gases.

Another object of this invention is to provide such a system which is especially applicable to self-service.

30 A further object of this invention is to provide a system which will require little or no attention other than to replenish the supply of liquefied gas.

35 Figure 1 is an elevational view, partly in vertical cross-section, of apparatus of this invention.

Figure 2 is an elevational view, partly in vertical cross-section, of a modification of the apparatus of Figure 1.

40 Figure 3 is an elevational view of the dispensing system with which the apparatus of Figure 1 is used.

Figure 4 is a plan view of the supporting member used with the present system.

45 With reference to Figure 1 of the drawings, the reference numeral 5 designates a container for liquefied gases, the contents of which are to be dispensed from the container as a liquid. The liquid feed or flash vaporization method of dispensing liquefied petroleum gases is known in the art. Attached to the wall of a building or to any suitable supporting surface, not shown in the drawings, and extending outwardly therefrom is a closed U shaped supporting member 6. Ver-

tical guides 7 are attached to the supporting member at spaced intervals and to horizontal cross-bars 8. The horizontal cross-bars intersect at an adapter 9. The adapter 9 is bored on several diameters forming a passageway therethrough, and is threaded at 10. A push-pin regulator 11 similar to that disclosed in the Patent No. 2,245,485 to Kenneth R. Lewis, issued June 10, 1941, is connected to the adapter by the threaded coupling member 12. The push-pin 13 of the regulator extends through the cylindrical opening 14 in the adapter; preferably the push-pin is square or hexagonal in cross-section providing passageways between the push-pin and the cylindrical opening 14. The conduit 15 of the regulator is pressed firmly against the resilient gasket 16 in the adapter by the coupling member 12 maintaining sealing relationship between the conduit and the adapter. The adapter is provided with a large cylindrical bore 17 at its upper end which contains a gasket 18. Attached to the bottom of the container 5 and extending therethrough is a valved connector 19 which is secured in the container in any suitable manner, for example, by welding. The connector 19 contains a valve 20, preferably a self-closing valve of the tire valve core or similar type.

When the container is in position for withdrawal of its contents as in Figure 1 of the drawings, the connector 19 of the container makes sealing engagement with the gasket 18 in the adapter. When connection is established between the cylinder 5 and the regulator 11 in this manner, the push-pin 13 opens the valve 20, allowing liquid from the container to enter the regulator. The liquid discharged from the regulator flows through an outlet pipe 21 to auxiliary equipment, not shown in the figure, where it is vaporized before passing to the gas consuming appliances. In operation, liquid from the cylinder 5 flows through the connector 19 and adapter 9 through the regulator 11 into the pipe 21 as required. When the cylinder 5 is empty, the customer lifts the cylinder off adapter 9 thereby allowing the valve 20 to close. The empty container is then replaced with a filled container.

The guard ring 22 on the base of the container surrounds the connector 19 providing protection against damage to the connector during transportation. The guard ring also acts as a supporting base for the container when transported or stored. The top of the container is provided with an outlet connection 23 which is attached to the container by welding. Within the outlet is a tap plug 24 in which is incorporated the usual safety devices comprising the fuse plug 25 and the safety relief valve 26. Attached to the outlet 23 are carrying handles 27 for convenience in transporting in the container. The regulator 11 is protected from the weather by the protective housing 29 which is open on the under side to allow access to the regulator and its associated fittings.

Figure 2 is a modification of the apparatus shown in Figure 1. Attached to the bottom of the container 30 is a tap plug 31 into which the connector 32 is screw-threaded. Sealing engagement between the tap plug and the connector is made by the gasket 33. The adapter 34 is attached to the horizontal cross-bars 8 of the supporting member by bolts 35. The connector 32 contains a valve 36 of the self-closing or tire valve core type. Attached to the connector 32 by means of the fitting 37 is a tube 38 which extends above the liquid level in the container.

When the container is in the position shown in the drawings the connector 32 makes sealing engagement with the gasket 40 in the adapter 34. The push-pin regulator 11 is attached to the adapter by means of conduit 41. The push-pin 42 of the regulator actuates the valve 36 of the connector allowing gas from the tube 38 to flow through the connector and adapter into the regulator 11 and through the pipe 43 to the customer's gas-consuming appliances.

In operation, gas from the container 30 is withdrawn through the pipe 43 as required by the consumer. Control of the flow of gas is governed by the regulator 11 which opens or closes the valve 36 in accordance with the demand for gas. The valve 36 acts as a throttling valve to reduce the pressure in the container to that required in the pipe 43. If desired, a secondary or second stage regulator may be interposed between the pipe 43 and the customer's service line to further reduce the pressure. When the container 30 is exhausted, it is removed from the supporting member 6 and replaced by a filled container.

Figure 3 is an elevational view showing the apparatus of Figure 1 in service in the gas dispensing system. Liquid from the container 5 is withdrawn from the bottom of the container through the regulator 11 and pipe 21 to a vaporizer 45. The liquid is vaporized and the vapors passed through the outlet pipe 46 and valve 47 to the second stage regulator 48. The second stage regulator discharges into the customer's service pipe 49 in accordance with the demand for the gas by the gas-consuming appliances.

Figure 4 is a plan view of the supporting member 6 showing the relationship of the various horizontal and vertical members 7 and 8 which position and support the container relative to the adapter and withdrawal connections.

The disadvantages of the present self-service systems, that is, the use of flexible couplings, is eliminated by the novel method by which connection is made between the self-service container and the pressure regulator attached to the customer's service pipe. It is to be understood that two or more containers may be used simultaneously to provide continuous and uninterrupted service of fuel during the interim required for replacing an empty container with a filled one.

I claim:

1. Equipment for storing and dispensing liquefied gas comprising a portable container having an opening in the bottom wall thereof, a connector secured in said opening, a dispensing passage in said connector, a valve for closing said dispensing passage, a tap plug in the top of said container, a valved pressure relief passage in said tap plug, a second passage in said tap plug, and means normally closing said second passage and responsive to abnormal temperatures to open the said second passage.

2. Equipment for storing and dispensing liquefied gas comprising a portable container having an opening in the bottom wall thereof, a connector secured in said opening, a dispensing passage in said connector, a tube attached to said connector in the interior of the container in communication with the said dispensing passage and terminating above the normal liquid level in the container, and a valve for closing said dispensing passage.

3. Equipment for storing and dispensing liquefied gas comprising a portable container having a valved fluid dispensing outlet in one wall there-

of, a tap plug in said container, a valved pressure relief passage in said tap plug, a second passage in said tap plug, means normally closing said second passage and responsive to abnormal temperatures to open the said second passage, and carrying handles attached to said tap plug.

4. A system for storing and utilizing liquefied gas comprising a support, an adapter attached to the support, a pressure regulator associated with the adapter, a delivery pipe connected to the pressure regulator, a container, a connector associated with the container, a self-closing valve in the connector urged into closing position by pressure in the container, means for maintaining a fluid tight connection between the adapter and the connector and means for actuating said valve to allow fluid from the container to flow through the connector and the adapter to the delivery pipe.

5. A system for storing and utilizing liquefied gas comprising a container having an opening in the bottom thereof, a connector secured in said opening, a dispensing passage in said connector establishing communication between the exterior and interior of the container, a self-closing valve for closing said dispensing passage and openable against pressure in the container, a supporting member for positioning and supporting the container, an adapter attached to the supporting member and coacting with the connector, a passage through said adapter, a delivery pipe in communication with said adapter, and means for actuating said valve to allow fluid from the container to flow through the connector and the adapter to the delivery pipe.

6. A system for storing and utilizing liquefied gas comprising a container having an opening in the bottom thereof, a connector secured in said opening, a dispensing passage in said connector establishing communication between the exterior and interior of the container, a self-closing valve for closing said dispensing passage and openable against pressure in the container, a supporting member for positioning and supporting the container, an adapter attached to the supporting member and coacting with the connector, a passage through said adapter, a push-pin pressure regulator associated with the adapter, and a dispensing pipe attached to the regulator, the push-pin of the pressure regulator extending through the adapter and coacting with said valve to actuate the same.

7. A system for storing and utilizing liquefied gas comprising a container having an opening in the bottom thereof, a connector secured in said opening, a support, an adapter attached to the support and coacting with the connector, a passage through said adapter, a delivery pipe in communication with said adapter, a dispensing passage in said connector establishing communication between the exterior and interior of the container, a tube attached to said connector in the interior of the container in communication with said dispensing passage and terminating above the normal liquid level in the container, a self-closing valve for closing said dispensing passage and openable against pressure in the container, and means for actuating said valve to allow fluid from the container to flow through the connector and adapter to the delivery pipe.

CHARLES MACSPORRAN.
